UNITED STATES PATENT OFFICE.

RAYMOND C. PENFIELD, OF CHICAGO, ILLINOIS.

BRICK-HANDLING APPARATUS.

Specification of Letters Patent. Patented Mar. 11, 1913.

1,055,490.

Application filed July 17, 1911. Serial No. 638,912.

To all whom it may concern:

Be it known that I, RAYMOND C. PENFIELD, a citizen of the United States, and resident of Chicago, county of Cook, State of Illinois, have invented an Improvement in Brick-Handling Apparatus, of which the following description, in connection with the accompanying drawings, is a specification, like letters on the drawings representing like parts.

In the present day manufacture of bricks on a large scale, wherein the green bricks, as delivered by an off bearing conveyer from the molding machine, are piled in hacked relation on drier cars to be moved in carloads to and through the drier tunnels and thence to the kiln for burning, it is essential that provision be made for a proper circulation of air between the units as assembled on the drier car, so that all the bricks on the car may be quickly and properly dried, and it is a further requisite that the bricks be delivered at the kiln in close compact formation on the car so that the entire carload may be handled en masse by a mechanical setter.

The present invention provides means whereby the bricks are spaced apart upon entering the drier tunnels to permit a quick effective drying, and again brought together in close formation upon leaving the drier and in readiness for lifting by the mechanical setter, such means having also provision for straightening and alining the brick units on the drier car, and in conjunction therewith, means for conveniently and expeditiously handling the drier cars as they are delivered to and from the drier. In the preferred embodiment shown the means and devices to accomplish these ends are mounted on and coöperate with a transfer car construction, adapted for delivering the loaded drier cars to the drier tunnels, and in a slightly modified form for transferring the drier cars from the drier tunnels to the kiln.

The invention will be more fully understood from the following detailed description, taken in connection with the accompanying drawings, and will thereafter be pointed out in the appended claims.

Referring to the drawings: Figure 1 is a side elevation of a transfer car equipped with my improved mechanism, a loaded drier car being shown thereon. Figs. 2 and

3 are complementary views which together constitute an enlarged plan of the transfer car apparatus. Fig. 4 is an end view taken in section approximately on the line 4—4 of Fig. 1. Fig. 5 is an enlarged detail side view with parts in section showing the means for controlling the movement of the slideable decks. Fig. 6 is a detail vertical section of a driving connection taken on line 6—6 of Fig. 1. Figs. 7 and 8 are detail plan and side elevations respectively of an operating mechanism for removing the drier cars from the transfer car. Fig. 9 is a side elevation, with an intermediate portion broken away, of the transfer car as constructed to deliver the drier cars from the drier tunnels to the kiln. Fig. 10 is a diagrammatic view of an illustrative system in which the present invention may be employed, and Fig. 11 is an enlarged vertical section through the drier car showing details of the sectional deck and of the means for moving the car.

The transfer car track 1 extends from a position convenient for the loading of the bricks from the off bearing conveyer, along across the entrance end of the drying tunnels. The transfer car is preferably composed of a structural steel framework 2 with wheels 3 suitably journaled thereto, as shown at 4, to run on track 1. This car has tracks 5 for a drier car or cars 6, only one drier car being usually carried by the transfer car which delivers the loads of bricks from the source of supply to the drier, while the transfer car which transfers the loads from the drier to the kiln preferably has provision to receive several drier cars, this being necessary because the transfer car at this end of the drier has longer runs than at the entrance end. The transfer car is adapted to be moved along its track by a motor 7, suitably mounted near one end thereof and in geared connection with one of the car axles as by gearing 8.

The drier car 6 has its platform composed of a series of sliding deck sections 9, 10, 11, 12, each adapted to hold a unit of bricks. These deck sections preferably have their tops formed of sheet iron as shown at 13, with their edges turned down over castings 14, as seen at 15, 16. These castings 14 are fitted for guided sliding movement over a number of structural steel T guides 17, se-

cured to the side rails 18, 19 of the drier car. The several deck sections 9, 10, 11, 12, shown as four in number, though this is merely illustrative, extend the length of 5 drier car 6 and have a limited sliding movement with relation to one another, being connected by having pins 20 fixed to the sides of each casting 14 engaged with elongated slots 21 in the ends of connecting links 10 220. The several deck sections are so proportioned relative to one another and the slots 21 are of such a length, that the tops 13 of the deck sections, when they are slid together, form a substantially continuous 15 platform with each top portion, adapted to receive a unit of bricks, while, when the deck sections are pulled apart as far as permitted by the slots 21, the brick units thereon are spaced apart so as to leave a substantial 20 space α for air circulation therebetween. The movement of these deck sections is controlled by laterally moving shutters 22, 23 at either side of the drier car, which are at the same time adapted to engage the sides 25 of the outer brick units on the car to align and straighten them. These shutters are composed of sheet steel plates 24 of the proper length and width to engage substantially the entire sides of the outer brick 30 units, these being fixed to rigid backing bars or plates 25 supported by rollers 26 on horizontal bars 27 supported in depending relation to a top framework 28 of the transfer car. This framework 28 is supported on 35 vertical structural beams 29 and the bars 27 are adjustably supported therefrom with some little freedom of movement by means of rods 30 with adjustable hangers 31 at their lower ends to engage the bars 27, this 40 depending arrangement of the bars 27 permitting some little horizontal transverse vibration or self adjustment of the shutters as requisite. The shutters 22, 23 are connected to be moved simultaneously toward 45 and from each other, and to effect the proper sliding movement of the deck sections 9, 10, 11, 12 thereby, hanger lugs 32 are fixed at the lower end of each shutter and these have pivoted thereto at 33 dogs 50 34 adapted to engage the outer deck sections 9, 12 to pull them apart, and by means of the links 22, to also pull the intermediate sections 10, 11 the proper distances apart 55 to permit proper circulation of air between the units.

The dogs 34 are drawn upward for engagement with the in-turned edges 15 of the deck tops by means of a coil spring 35 secured to a pin 36 on the dogs 34 and at 37 60 to the hangers 32. The engaging beak 38 of dog 34 is not rigidly fixed thereto, but is mounted to turn on an axis 39 near the outer end of the dog and has rigid therewith a pinion segment 40 engaged with a 65 similar segment 41 pivoted to the dog at 42.

The pinion segment 41 has extending therefrom an arm 43 urged up against the pin 36 by a light spring 44. The arm 43 is normally further held up against the pin 36 by a catch 45 pivoted to the dog at 46 and urged into engagement with the end of the arm 43 by a spring 47. When the parts are held in this position the beaks 38 are held locked in position to engage the outer deck sections 9, 12 to pull them apart, and as the pins 20 come to the outer ends of the slots 21 the intermediate deck sections 10, 11 will be also pulled apart, the extent of their separation being likewise limited by similar link and slot connections so that all the units are spaced apart the same distance. Adjustably fixed to the framework of the transfer car in a socket 48 thereon is a rod 49 adapted to be clamped in properly adjusted position by a set screw 50 in said slot. This rod projects inward toward the dog 34 and is so adjusted that just as the deck sections are fully spaced apart its inner end 51 engages the end of catch 45 which projects beyond its pivot as seen in Fig. 5, to disengage said catch from the arm 43. Thereupon further outward movement of the shutters 22, 23 will result in the beaks 38 turning around on their pivots 39 until they are disengaged from the deck sections, it being understood that the movements just described take place as the shutters 22, 23 are being simultaneously drawn apart or outward. The outer ends of the dogs 34 are beveled as seen at 52 and the beaks 38 form a continuation of such bevel, so that the dogs are readily forced inward to snap under the inturned edges 15 as clearly apparent from Fig. 5.

The means for effecting simultaneous in and out movement of the shutters 22, 23 may vary widely in character without departing from the invention, but in the preferred embodiment shown this movement is effected from a shaft 53 suitably journaled in the transfer car framework and having fixed thereto an operating arm 54. The shaft 53 also has fixed thereon bell crank levers 55 shown as three in number, one arm of these levers having pivoted thereto at 56 links 57 which are connected at 58 to the top portion of the adjacent shutter 22 at the two sides and the middle thereof respectively. The other arm 59 of each of the bell crank levers has pivoted thereto at 60 the upper end of an adjustable turn buckle link 61, whose lower end is engaged at 62 with one arm of a bell crank lever 63 turning about an axis 64 and having its other arm pivoted at 65 to a link 66, engaged with the lower end of the shutter 22 at 67; it being understood that there are three of these links at each side and at the middle of the shutter corresponding to the links 57, and that the links 66 and their operating bell cranks cor- 100 105 110 115 120 125 130

respond in size and arrangement to the links 57 and bell cranks 55 so that the top and bottom portions of the shutter 22 move in parallelism with each other. The shutter 23 is connected for movement in synchronism with the shutter 22 by means of an arm 68 fixed to the shaft 53 and extending downward therefrom to which arm is pivoted at 69 a rod 70 adjustable in length and connected at its other end to an arm 71 fixed to and extending upward from a shaft 72 journaled in the uprights 29 of the transfer car framework. The shaft 72 has fixed thereon a set of bell crank levers 73 corresponding to the levers 55 and these have one arm connected by links 74 to the upper portion of the shutter 23. The other arm of these levers is pivotally connected by means of adjustable links 75 with one arm of bell cranks 76 pivoted at 77 in the framework and whose other arms have connected thereto links 78 fixed to the lower portion of the shutter 23. Thus upon oscillation of the arm 54, the shutters are moved in and out in parallelism with each other to engage the sides of the brick units and straighten them as they are moved inward and to properly separate the units on the car for air circulation therebetween as they are drawn outward.

The arm 54 is oscillated by a link or pitman connection 79 upon crank 80 fixed on a shaft 81. This pitman connection has a block 82 at its end adjustable in a lengthwise slot 83 in the arm 54 by means of a screw bolt 84. The upper portion of pitman connection 79, pivoted to the block 82, is bifurcated as shown at 85 and a stout coil spring 86 is interposed between a seat 87 at the base of this bifurcated portion and an abutment 88 at the top of rods 89, slideable through the bifurcated upper portion of the pitman. These rods 89 have fixed abutments 90 against which the upper part of the pitman is pressed by the spring 86. The purpose of this construction is to provide a yielding connection between the operating mechanism and the shutters so that, if these be prevented from moving inward for any reason, such as the car not being in proper position, the spring 86 yields, avoiding breakage or damage of any of the parts. The lower ends of the rods 89 are adjustably fixed to a bearing block 91 in which a crank pin with a crank 80 is fitted. The shaft 81 is suitably journaled in bearings 92 on the transfer car framework and is driven from a worm wheel 93. This worm wheel is loosely journaled on the shaft and is adapted to be connected in driving engagement therewith by means of a pin 94 carried by a flanged collar 95 slideable on the sleeve 96 of a flange member 97 keyed to the shaft 81 and having one or more holes 98 therethrough to receive the pin 94. The hub of the worm wheel 93 has a registering series of lateral holes 99 therein so that, as it revolves, the pin 94 may be slid through hole 98 into a hole 99 thus locking the worm wheel to the shaft. Driving impulse is imparted to the worm wheel 93 from a worm 100 fixed on a shaft 101 journaled in bearings 102 in the framework, this shaft being driven from a motor 103 through back gearing 104, a flexible coupling 105 being interposed in the shaft 101 to relieve the motor of shocks and of any vibration of the car. The motor 103 may run continuously during the operation of the car and may have a suitable rheostat controller. The clutching collar 95 is adapted to be slid so that its pin 94 will connect the driving mechanism to operate the shutters, or disconnect the same at will, by means of a lever 106 fixed to a rock shaft 107 journaled in the base of the framework at 108 and having fixed to its inner end an upstanding arm 109 connected by means of a link 110 to a clutch shipper 111 engageable in an annular groove 112 of the sliding clutch flange. The motor through the shaft 101, and the worm wheel 93 driven thereby, is adapted to transmit power as required for moving the drier cars along the tracks 5 cross wise of the transfer car especially to remove them therefrom. To this end the worm wheel 93 has keyed on a lateral sleeve 113 thereof a spur wheel 114 meshing with a gear 115 fixed on a shaft 116 suitably journaled in the base of the transfer car frame. This shaft has loosely mounted thereon opposite bevel gears 117, 118 held in spaced apart relation by journal bearings 119, 120 so that the teeth of both are engaged with a bevel pinion 121 fixed on a shaft 122 journaled in the base of the transfer car frame and extending lengthwise thereof. Either of the bevel gears 117, 118 is adapted to be clutched in driven engagement with the shaft 116 to drive the shaft 122 in either direction at will by means of a clutch collar 123 slidably keyed on shaft 116 and having pins 124 projecting at either side and adapted to engage in holes 115 in the sides of the bevel gears. The gears 117, 118 are spaced apart relative to the clutch collar and to the pins 124 so that either of these may be engaged with the shaft to be driven or both disengaged therefrom.

The shaft 122 extends underneath the track or track sections 5 on the transfer car and has fixed thereon a gear 125 in driving engagement with a pinion 126 on a counter-shaft 127, which also carries a sprocket wheel 128 for a sprocket chain 129, this chain running over an idler sprocket wheel 130 mounted at the other side of the transfer car. The sprocket wheels 128 and 130 are of a size and are mounted so that the upper reach of the sprocket chain extends just underneath the axles 131 of the drier

car, and it may be supported in this position by a guide 129^a fixed to the transfer car frame. The sprocket chain carries a lug or finger 132 extending up far enough to engage an axle of the drier car so that when the sprockets are driven the drier car is moved off the transfer car on to a stationary track. It is apparent, in the case of a transfer car shown in Figs. 1 to 16, which has only 10 a single stall to receive one drier car, this being the type of transfer car employed in delivering the drier cars to the drier tunnels, that the movement of the sprocket chain 129 can be readily controlled by shifting the clutch 123. The clutch collar 123 is adapted to be shifted at will by a shifter yoke 133 fixed on a rock shaft 134, this having an arm 135 connected by a link 136 to a similar arm 137 fixed on a rock shaft 15 138 journaled in the base of the frame and extending to the front of the car where it has an operating lever 139.

In the case of the transfer car which is designed to deliver the drier cars from the 20 drier tunnel to the kiln, this having, as before explained, stalls for several drier cars side by side, it is essential that means be provided so that the drier cars can be moved one by one as required from the transfer car 25 and to this end each driving sprocket wheel 128', is loose on its power shaft 127' which corresponds to the shaft 127 before described, and connection is made to operate the sprocket chain 129 by a clutch 140 slidably splined, or otherwise secured to the shaft 127' and operated by a lever and link connection 141. A suitable take-up may be provided for the idler sprocket wheel 130, this being mounted in adjustable bearings 30 142 which are moved as required by adjusting bolts 143.

In Fig. 9 one of the plural stall transfer cars for delivering the drier cars from the drier to the kiln is shown with its central portion broken away. This car in practice usually has from two to six stalls for a like 45 number of drier cars, and except for the clutches for controlling the individual sprocket wheels 128' and the plural stall arrangement, may be formed substantially like the car shown in Fig. 1, or the opening dog elements may be omitted, since this car principally operates on the brick units to close them together and straighten them 50 55 after having been previously opened by the transfer car which delivered them to the drier tunnels.

The car shown in Fig. 9 has certain other minor differences over that of Figs. 1 to 6, 60 the pitman 79' corresponding to the pitman 79 being rigid and operating a horizontal reciprocating bar 144 which controls all the shutters and is connected to the several bell cranks by a series of horizontally extending 65 yielding connections 145. In this form

of car the operating levers 106' and 139' corresponding to the levers 106 and 139 are engaged by means of bevel gear connections 146, 147 to rock shafts 107' and 138' corresponding to the shafts 107 and 138. The 70 electric energy for operating the motor is taken from a line wire 148 by means of a usual trolley 149 pivoted at 150 to a support 151 vertically adjustable in the car framework. In practice suitable brakes for 75 the cars may be provided but as these form no part of the present invention it is deemed unnecessary to show the same herein.

In operation the bricks, after being formed and cut at the molding machine A, 80 see Fig. 10, or otherwise produced, and delivered therefrom by the off bearing conveyor B, are removed either by hand or by mechanical transferring means to the drier cars 6, packed in close formation. The 85 drier cars after being loaded, are pushed on to the transfer car, this being arranged so that the track section 5 for the drier car mounted thereon may be brought into alignment with the main drier car track C. The 90 drier car being positioned on the transfer car, the shaft 81 is connected with the driving motor 103 by moving the lever 106 to throw in clutch pin 94 and the pitman and bell crank connections move the shutters 22, 23 toward each other against the sides of the outer units of bricks straightening and aligning them and removing irregularities in the entire load, which may have been occasioned by carelessness in the hand stacking, 95 or otherwise. Thereupon the movement of the crank 80 causes the shutters 22, 23, after completing their inward movement, to move apart, and in this movement the beaks 38 of the dogs 34 engage with the rolled under 100 tops of the outer deck sections after the shutters have moved a short distance and drawn them outward. After these outer deck sections have moved some little distance, determined by the length of the slots 110 21, the links 220 engage to draw the two center deck sections apart until the loads on all the deck sections are spaced apart from one another and from the shutters so as to leave vertical channels for air circulation 115 between all the units and permitting a relatively quick effective drying of all the bricks in the carload. The drier cars, with their decks in this open formation, are now run to the drier tunnels D and after the 120 drying process is completed, they are run out therefrom into the other transfer car which has its shutters operated in the manner first described to slide the deck sections together again bringing the entire loads on the several drier cars into a compact and close formation so that an entire car load may be grasped and lifted by the mechanical setter for bodily transfer to the burning kiln. 125 130

I consider the mechanism typified by the shutters for straightening and alining the load and bringing it to close formation, as also the mechanism typified by the opening dog elements for pulling the deck sections apart, to be broadly new and I desire to cover these irrespective of structural details. I also consider the improved mechanism operating in conjunction with the foregoing devices for removing the drier cars from the transfer car to be new and I do not desire to be limited to the details shown for effecting this result.

While the improved mechanism is shown and described for illustration in a system operating from the source of brick supply to the drier tunnels and thence to the burning kiln, it is to be understood that this is in no way restrictive and is set forth merely to explain in detail a special application of the invention. I therefore do not desire to be limited to any special uses of the improved mechanism which is of general application, nor as to any special features of construction except as set forth in the appended claims.

Having described my invention, what I claim as new and desire to secure by Letters Patent is as follows:

1. An apparatus of the kind described, comprising a car having a permanent platform base for receiving a stacked load of brick, means for separating a load on said car into sections with an air space therebetween, and means for positively closing said sections together.

2. An apparatus of the kind described, comprising a car having a permanent platform base for receiving a stacked load of brick, means for separating a load on said car into sections with an air space therebetween, and means for closing said stack sections together and at the same time straightening the stack.

3. An apparatus of the kind described, comprising a carrier for stacked loads of bricks, means for positively separating the stack into sections with an air space therebetween, and means for positively closing said sections together.

4. An apparatus of the kind described, comprising a carrier for stacked loads of bricks, means for positively separating the stack into sections with an air space therebetween, and means for positively closing said sections together, and at the same time straightening and alining the stack.

5. An apparatus of the kind described, comprising a car having a sectional deck to receive a stacked load of bricks, and means at opposite sides of the car arranged to pull the opposite sides of the deck in opposite directions for effecting a definite separation of the deck sections to permit air circulation between portions of the stack thereon.

6. An apparatus of the kind described, comprising a car having a sectional deck, means at opposite sides of the car arranged to pull the opposite sides of the deck in opposite directions for effecting definite separation of the deck sections to permit air circulation between portions of the stack, and means for closing the sections together to constitute a substantially continuous platform.

7. An apparatus of the kind described, comprising a car having a deck formed in sections with the sections connected for limited relative sliding movement, means at opposite sides of the car arranged to pull the opposite sides of the deck in opposite directions for separating said sections, and means for closing the sections together at will to form a substantially continuous platform.

8. An apparatus of the kind described, comprising a carrier having a deck formed in sections, the intermediate sections being connected to the outer sections by links permitting limited relative movement, and means on the carrier for exerting impulse simultaneously on the outer sections in opposite directions to pull the several sections apart.

9. An apparatus of the kind described, comprising a carrier having a deck formed in sections adapted to receive a stack of bricks, the intermediate sections being connected to the outer sections by links permitting limited relative movement, means for engaging the outer sections to pull the several sections apart, and means for moving the sections together, said means having also provision for straightening and alining the stack on said deck.

10. An apparatus of the kind described, comprising a carrier having a deck formed in relatively movable sections adapted to receive a stack of bricks, and means for closing the sections together when separated, and at the same time straightening and alining the stack on said deck.

11. An apparatus of the kind described, comprising a carrier having a deck formed of relatively separable sections, means for closing the sections together when separated, and a shutter arranged to engage the side of the brick stack to straighten and aline the same.

12. An apparatus of the kind described, comprising a carrier having a deck formed in relatively separable sections to receive a brick stack and permit the same to be separated into parts with an air space therebetween, and shutters for simultaneously engaging opposite sides of the stack to straighten and aline the same.

13. An apparatus of the kind described, comprising a carrier having a platform to receive a stack of bricks, and means movable up against a side of the stack on the

carrier formed to press evenly and equally against the several layers of bricks forming a stack to straighten and aline the stack.

14. An apparatus of the kind described, comprising a carrier having a platform to receive a stack of bricks, and means simultaneously movable against opposite sides of the stack formed to press evenly and equally against the several layers of bricks forming a stack to straighten and aline the same.

15. An apparatus of the kind described, comprising a carrier having a sectional deck to receive a stacked load of bricks, the sections being capable of limited separation to provide air spaces between portions of the stack, and vertical shutters simultaneously movable against opposite sides of the stack formed to press evenly and equally against the several layers of bricks forming a stack, to straighten and aline the same.

16. An apparatus of the kind described, comprising a carrier having a sectional deck to receive a stacked load of bricks, the sections being capable of limited separation to provide air spaces in the stack, means for closing the sections together, and vertical shutters connected with said closing means and simultaneously operable upon opposite sides of the stack formed to press evenly and equally against the several layers of bricks forming a stack to straighten and aline the same as its parts are brought together.

17. An apparatus of the kind described, comprising a carrier having a deck formed of relatively separable sections to receive a load and provide air spaces between parts thereof, operating mechanism for separating the deck sections, having a dog to engage an outer section, and means for tripping said dog to disengage it at the desired limit of separating movement.

18. An apparatus of the kind described, comprising a carrier having a deck formed in sections capable of limited relative separation, operating mechanism having dogs adapted to engage the outer deck sections to pull the same apart, and means for disengaging said dogs at the desired limit of separating movement.

19. An apparatus of the kind described, comprising a carrier having a deck formed in sections capable of limited relative separation, operating mechanism having dogs for engaging the outer sections to pull them apart, means for disengaging the dogs at the desired limit of separating movement, and means for closing the sections together and at the same time alining and straightening the stack.

20. An apparatus of the kind described, comprising a carrier having a deck formed in sections capable of limited relative separation, means for moving said sections apart to a definite extent and for closing them to-

gether at will, and an operating device for said means having a yielding connection therewith to prevent damage from improper operation of the mechanism.

21. An apparatus of the kind described, comprising a transfer car, a drier car mounted thereon, and means for manipulating the stacked load on said drier car while the same is positioned on the transfer car to leave air spaces between portions thereof.

22. An apparatus of the kind described comprising a transfer car, a drier car mounted thereon, and means mounted on said transfer car for manipulating a stacked load on said drier car to provide air spaces between parts thereof and to bring the stack compactly together at will.

23. An apparatus of the kind described, comprising a transfer car having provision to receive thereon a drier car, a drier car having a deck formed in separable sections to receive a stacked load, and means mounted on said transfer car for controlling the position of said deck sections.

24. An apparatus of the kind described, comprising a transfer car, a car to be loaded carried thereby having a deck formed in separable sections, means mounted on said transfer car for effecting a definite separation of said deck sections, and means for closing the deck sections together.

25. An apparatus of the kind described, comprising a transfer car, a car adapted to receive a stacked load of bricks carried thereby, and means mounted on said transfer car for alining and straightening a stack of bricks on said second car.

26. An apparatus of the kind described, comprising a transfer car having a stall to receive a drier car, a drier car having a deck formed in separable sections, means mounted on said transfer car for moving said deck sections apart or together at will, and vertical shutters arranged to move against the sides of a brick stack on said drier car to straighten and aline the same.

27. An apparatus of the kind described, comprising a transfer car, a drier car mounted thereon having a deck formed in sections capable of limited separation, and means mounted on said transfer car at either side of said drier car for controlling the movement of said separable sections to bring parts of the load thereon to open or closed formation at will.

28. An apparatus of the kind described, comprising a transfer car, a drier car mounted thereon, interconnected means carried by said transfer car and having parts operable at both sides of said drier car to open up a stacked load thereon for drying, or to close such load together for bodily lifting at will.

29. An apparatus of the kind described,

- comprising a transfer car, a drier car mounted thereon, vertical shutters guided on supports carried by said transfer car and operable at either side of said drier car to 5 align and straighten a load thereon, and interconnected means for simultaneously operating said shutters.
30. An apparatus of the kind described, comprising a transfer car, a drier car 10 mounted thereon having a deck formed in separable sections, vertical shutters guided in supports on said transfer car on opposite sides of the drier car, and means for simultaneously controlling a separating and 15 closing movement of said deck sections and operating said shutters to press against the sides of a stacked load on said drier car to straighten and align the same.
31. An apparatus of the kind described, 20 comprising a transfer car having provision to receive thereon a drier car, means carried by said transfer car for manipulating a stacked load on the drier car, and means for controlling the movement of a drier car on 25 said transfer car.
32. An apparatus of the kind described, comprising a transfer car having provision to receive thereon a drier car and carrying means for manipulating a load on such drier 30 car to bring the same to open formation, and means also mounted on said transfer car for moving said drier car therefrom.
33. An apparatus of the kind described, 35 comprising a transfer car, a drier car adapted for movement on to and off from said transfer car and having a deck to receive
- a stacked load, means carried by said transfer car for separating such load into parts with air spaces therebetween, and means for moving said drier car from said transfer 40 car at will.
34. An apparatus of the kind described, comprising a transfer car having provision to receive a plurality of drier cars, and means for simultaneously manipulating 45 stacked loads on said secondary carriers to bring each stacked load into close formation so that it can be bodily-lifted by a mechanical lifter.
35. An apparatus of the kind described, 50 comprising a transfer car having provision for receiving a plurality of drier cars, means carried by said transfer car for simultaneously manipulating the loads on the several drier cars to bring the same into close and aligned formation to permit handling by 55 a mechanical lifter.
36. An apparatus of the kind described, comprising a transfer car having provision to receive a plurality of drier cars, means 60 for manipulating loads on the several drier cars to bring the same into close and aligned formation, and means for effecting controlled movement of each drier car individually at will.

In testimony whereof, I have signed my name to this specification, in the presence of two subscribing witnesses.

RAYMOND C. PENFIELD.

Witnesses:

C. V. MERTENS,
F. L. HOPLEY.

Correction in Letters Patent No. 1,055,490.

It is hereby certified that in Letters Patent No. 1,055,490, granted March 11, 1913, upon the application of Raymond C. Penfield, of Chicago, Illinois, for an improvement in "Brick-Handling Apparatus," an error appears in the printed specification requiring correction as follows: Page 7, line 46, for the words "secondary carrier" read *drier cars*; and that the said Letters Patent should be read with this correction therein that the same may conform to the record of the case in the Patent Office.

Signed and sealed this 8th day of April, A. D., 1913.

[SEAL.]

C. C. BILLINGS,

Acting Commissioner of Patents.

- comprising a transfer car, a drier car mounted thereon, vertical shutters guided on supports carried by said transfer car and operable at either side of said drier car to aline and straighten a load thereon, and interconnected means for simultaneously operating said shutters. 5
30. An apparatus of the kind described, comprising a transfer car, a drier car 10 mounted thereon having a deck formed in separable sections, vertical shutters guided in supports on said transfer car on opposite sides of the drier car, and means for simultaneously controlling a separating and 15 closing movement of said deck sections and operating said shutters to press against the sides of a stacked load on said drier car to straighten and aline the same.
31. An apparatus of the kind described, 20 comprising a transfer car having provision to receive thereon a drier car, means carried by said transfer car for manipulating a stacked load on the drier car, and means for controlling the movement of a drier car on 25 said transfer car.
32. An apparatus of the kind described, comprising a transfer car having provision to receive thereon a drier car and carrying means for manipulating a load on such drier 30 car to bring the same to open formation, and means also mounted on said transfer car for moving said drier car therefrom.
33. An apparatus of the kind described, 35 comprising a transfer car, a drier car adapted for movement on to and off from said transfer car and having a deck to receive
- a stacked load, means carried by said transfer car for separating such load into parts with air spaces therebetween, and means for moving said drier car from said transfer 40 car at will.
34. An apparatus of the kind described, comprising a transfer car having provision to receive a plurality of drier cars, and means for simultaneously manipulating 45 stacked loads on said secondary carriers to bring each stacked load into close formation so that it can be bodily-lifted by a mechanical lifter.
35. An apparatus of the kind described, 50 comprising a transfer car having provision for receiving a plurality of drier cars, means carried by said transfer car for simultaneously manipulating the loads on the several drier cars to bring the same into close 55 and alined formation to permit handling by a mechanical lifter.
36. An apparatus of the kind described, comprising a transfer car having provision to receive a plurality of drier cars, means 60 for manipulating loads on the several drier cars to bring the same into close and alined formation, and means for effecting controlled movement of each drier car individually at will. 65
